UNITED STATES PATENT OFFICE

98,485

DESIGN FOR A BEVERAGE DISPENSING DEVICE

John M. Travis, St. Louis, Mo.

Application October 21, 1935, Serial No. 59,144

Term of patent 14 years

To all whom it may concern:

Be it known that I, John M. Travis, a citizen of the United States, residing at St. Louis, State of Missouri, have invented a new, original, and ornamental Design for a Beverage Dispensing Device, of which the following is a specification, reference being had to the accompanying drawing, forming a part thereof.

Figure 1 is a top plan view of the beverage dispensing device showing my design; Fig. 2 is a front elevational view; and Fig. 3 is a side elevational view thereof.

I claim:

The ornamental design for a beverage dispensing device as shown.

JOHN M. TRAVIS.
